SURFACE COATING APPARATUS

Robert A. Moore, Cleveland, Ohio, assignor of
one-tenth to William J. Wesseler, East Cleve-
land, Ohio

Application March 8, 1933. Serial No. 660,068

6 Claims. (Cl. 91—62.6)

This invention as indicated relates to a surface coating apparatus. More particularly, it comprises an apparatus peculiarly adapted to the placing of stripes upon various articles. It is also suitable for applying a coating in elongated strips of various widths. The film applied to the surface may comprise paints of various character in the broad sense, including lacquers, bronzes, and also oxide pastes. Such oxide pastes 10 are used in connection with enamelware ornamentation or on vitreous surfaces, and heretofore have offered difficulties in connection with their decoration during manufacture, for the reason that stencils or templates were used and 15 the material was applied through a single opening in order to sufficiently protect the margins. Where a plurality of closely juxtaposed parallel stripes under this prior practice are to be placed about an article, as is most frequently required 20 in the ornamentation thereof, a single stripe is placed and is then subjected to the burning operation in a furnace and thereafter the operation of striping and burning is repeated for each stripe, entailing much expense for labor 25 and handling as well as for the burning operation. With the present device, articles of this character can be striped with any required number 30 of parallel stripes and the entire series of stripes can be burned in with a single heat in the furnace.

The principal object of the present invention is to provide an improved coating tool for applying films of coating of various materials to a surface.

Another object of the invention is to provide a tool peculiarly adapted for applying stripes of any desired width and operating efficiently to provide very broad stripes as well as on stripes of such degree of fineness of line that they are 40 entirely impractical for application to a surface by a striping brush in the manner now generally used in the industry. The fineness of line possible with the apparatus is adequate for use in a draftsman's tool, whereby a constant supply of ink may be made available without the loss of time and difficulty of keeping the instruments clean, as is presented when a bow pen is used for like operations.

Another object of the invention is to provide 50 a reservoir feeding by gravity against the outer surface of a feed roll or wheel having a surface especially prepared to receive a film of coating material and to place the same against the surface to be covered as a continuous operation with 55 sharp clean-cut edges.

Another object of the invention is to provide a surface coating tool having an applicator roll or wheel contacting directly with the surface at one side thereof and contacting directly with the fluid in the reservoir at another side thereof and 60 carrying about its periphery in the form of parallel capillary filaments the material to be applied to such surface.

Another object of the invention is to provide a film applying roll or wheel carrying about its 65 circumference a series of parallel grooves preferably so closely positioned to each other as to form capillary channels to hold minute filaments of liquid within the spaces between the dividing members and to carry such filaments of liquid 70 into contact with the surface to be coated and placing the same into contact with such surface.

Another object of the invention is to provide a portable reservoir of suitable size together with a feeding channel and a roll or wheel supported adjustably with reference thereto 75 preferably with a micrometer adjustment.

Another object of the invention is to provide a surface coating tool having a coating wheel supplied from a reservoir and having a handle 80 adjustable to various angular positions with reference thereto.

Another object of the invention is to provide a tool having a handle formed with a sleeve adapted for a slight degree of motion about the handle 85 shank in a rotary direction to compensate for the personal factor of the user, such as slight vibration or unsteadiness introduced through breathing usually preventing mechanically accurate striping and the like.

Another object of the invention is to provide a 90 micrometer adjustment between the capillary feed roll or wheel and the reservoir whereby the spacing between said elements may be regulated to microscopic clearances suitable for handling any 95 type of film to be applied to the surface.

Other and further objects of the invention will appear in the course of the following description.

To the accomplishment of the foregoing and related ends, said invention, then, consists of the means hereinafter fully described and particularly pointed out in the claims, the annexed drawing and the following description setting forth in detail certain mechanism embodying the invention, such disclosed means constituting, however, but several of the various forms in which the principle of the invention may be used.

In said annexed drawing:

Figure 1 is a front elevation showing a striping 110

tool with a fountain reservoir shown partly in section at the side thereof;

Figure 2 is a side elevation of the device shown in Figure 1 with the fountain reservoir omitted and the handle being indicated in a second position of adjustment;

Figure 3 is a fragmentary vertical sectional detail view, taken along the line 3-3 shown in Figure 2, looking in the direction of the arrows and showing the lower portion of the device, and the connection of the fountain reservoir with the liquid supply chamber;

Figure 4 is a top plan view of the body portion of the apparatus as seen along the line 4-4, shown in Figure 1, looking in the direction of the arrows with the handle yoke being shown in section;

Figure 5 is an enlarged sectional detail view of the device, as seen along the line 5-5, shown in Figure 2, looking in the direction of the arrows;

Figure 6 is a view similar to Figure 5, taken along the line 6-6, shown in Figure 5, looking in the direction of the arrows; and

Figure 7 is a side elevation of a modified form of striping tool with a fountain reservoir shown at the front thereof and showing a guide member in operative adjustment on the handle portion.

In the form of construction shown in Figures 30 1 to 6 of the drawing, the apparatus comprises a body member 1 having a transverse recess adjacent its lower portion preferably in the form of a cylindrical chamber 2 open at one side to provide a passageway for coating fluid. Side 35 plates 3, 4, of slightly less width than the width of the body side are secured in shallow channels to the respective sides of the body by means of screws 5, 6, respectively, which engage in screw-threaded openings within the body, which as 40 shown in Figure 3 may comprise a continuous screw-threaded bore 7 extending completely through the body parallel to and spaced slightly above the reservoir. The side plates are provided with enlarged openings 8, 9, at the points 45 where the respective screws 5, 6, pass through the same to afford sufficient clearance to allow the micrometer adjustment presently to be described before such screws are turned to clamping adjustment. The side plates extend downwardly 50 below the body member and are provided with alined openings 11, 12, to provide bearings for the stub shafts 13, 14, projecting outwardly from the hub bosses 15, 16, to the feed roll or wheel 17.

The feed roll is a structure particularly formed 55 to receive a liquid coating from a reservoir or chamber, and to carry the same on its surface as a thin film or series of parallel filaments to the surface to be coated or other point of application which may include an intermediate trans- 60 fer to another roll or transfer surface as one element of a coating process. It has been found that a suitable film transfer surface for the feed roll may be provided by forming the same with parallel circumferential grooves 18 closely juxtaposed and of narrow width. The number of 65 grooves and the width of each groove may vary to some extent, but each such groove must be fine enough to carry the liquid in the form of a filament within the same and to apply such filament 70 to a surface without forming an irregular margin or "ragged edge" on the stripe or strip of coating material laid upon the surface. These grooves may be designated "capillary grooves" in view of their retaining the coating liquid much after 75 the manner of capillary tubes. The roll surface

between the grooves is in the form of sharp thin edges which prevent the roll squeezing the film sidewise upon contact with a surface by the bottom portion of the roll. The fine lines of contact of the parallel sharp edges on the roll cause no lines between the filaments after application to the surface as the light transverse liquid flow obliterates such lines immediately before the coating sets or reaches a state of repose upon the surface.

It has been found that by placing one hundred grooves to the inch a very effective liquid transfer surface can be provided, but the number may be varied somewhat in accordance with the character of the liquid to be applied.

A highly tempered steel roll has been found to be desirable and heat treatment at 1425 degrees F. has been used to provide satisfactory rolls. As stated, lines may be formed of various widths. A line $\frac{1}{4}$ of an inch wide can be laid down as well as broad bands suitable for street markings. In the latter case, direct contact of the roll with the surface may be avoided by a scraper to remove the film from the grooves and a brush to apply the same to the surface.

The depth of the groove may be varied, but a depth of from .006 to .012 of an inch has been found satisfactory.

The supplying of liquid to the surface of the roll is preferably accomplished by forming a recess 21 in the bottom wall of the liquid chamber 2 of the body, such recess being of a size to conform to the upper surface of the roll with a fractional portion of the roll preferably projecting slightly above or in line with the bottom surface of the liquid chamber when the roll is clamped tightly against said bottom face of the body. In this position the liquid chamber is substantially sealed at the bottom.

A very slight outward movement of the roll will 115 permit the roll to rotate and carry a thin film of liquid on its surface. This adjustment of the roll toward or away from the bottom of the liquid chamber is accomplished by means of adjusting screws 22, 23, having fine threads engaging threaded sockets 24, 25, in the top of the body, and each carrying around its upper end an extension collar 26, 27, respectively, which is received in a lateral recess 28, 29, respectively in the upper inner portions of the side plates 3 and 4 which project 125 slightly above the top of the body member. Suitable slots 31, 32, in the top of the screws permit micrometer adjustment of the plates and their associated roll, the parts when adjusted being clamped by means of the screws 5, 6.

The fountain reservoir preferably comprises a cylindrical member 33 with an inclined lower wall 34 sloping toward a nipple adapted to be received in an aperture 35 and frictionally held in the side plate 3 in alinement with the fluid chamber 2. 135 The reservoir is closed at the top by means of a cap 36 having a flange fitting within the open top of the fountain reservoir and provided with an air vent 37.

Various types of handles may be used, but the 140 type shown in Figures 1, 2 and 4, is preferable, comprising a yoke 41 pivoted on screws 42, 43, engaged in the side plates 3 and 4. The handle proper comprises a shank 44 having a screw threaded lower portion engaged by a collar 45 145 adapted to be adjusted into clamping engagement with a guide member which may be engaged through a transverse hole 46 immediately above the screw-threaded portion of the handle. A knurled sleeve 47 is engaged over the handle shank 150

- having a slot or notch 48 to provide for the shank of a screw 49 having a head 51 adapted to overlie the adjacent portion of the sleeve and clamp the same against movement. The slot is wider than the screw shank and when the head of the screw is slightly relieved from engagement with the sleeve permits oscillation of the sleeve in proportion to the width of the notch 48 to compensate for slight unsteadiness of the operator.
- 10 The modified form of construction shown in Figure 7 has substantially all the elements heretofore described, but provides an aperture in the front wall 61 of the body to receive the nipple of the fountain reservoir 62. The handle 53 is shown as applied directly to the rearward wall 64 of the body. The guide member 65 in the form of a bent wire member is shown in operative position. The loose sleeve on the handle is omitted from the showing in Figure 7, but it is to be understood could be used if desired on this structure as well as the other forms described.
- 15 Other modes of applying the principle of my invention may be employed instead of the one explained, change being made as regards the mechanism disclosed, provided the means stated by any of the following claims or the equivalent of such stated means be employed.
- 20 I therefore particularly point out and distinctly claim as my invention:
- 30 1. An apparatus of the character described having, in combination, a body, a chamber within said body for a coating liquid, a discharge opening for said liquid in the base of said chamber and presenting an elongated concave recess across a portion of its under surface, a roller of like curvature to said recess, a pair of plates on opposite sides of said body and non-rotatable with reference thereto for pivotally supporting said roller with a portion thereof engaged within 35 said recess and holding said roller in axial parallelism with said recess, and means for positively moving said plates to change the position of said roller with reference to said discharge opening.
- 40 2. An apparatus of the character described having, in combination, a body, a chamber within said body for a coating liquid, a discharge opening for said liquid in the base of said chamber and presenting an elongated concave recess across a portion of its under surface, a roller of like curvature to said recess, a pair of plates on opposite sides of said body for pivotally supporting said roller with a portion thereof engaged within said recess, means for positively moving said plates to change the position of said roller with reference to said discharge opening, and means for 45 locking said side plates against movement.
- 50 3. An apparatus of the character described having, in combination, a body, a chamber within said body for a coating liquid, a discharge opening for said liquid in the base of said chamber and presenting an elongated concave recess across a portion of its under surface, a roller of like curvature to said recess, a pair of plates on opposite sides of said body and projecting above and below the same for pivotally supporting said
- 5 roller with a portion thereof engaged within said recess at one end of said side plates, respectively, concave recesses in the inner faces of the respective side plates at their opposite ends, a pair of adjusting screws engaging screw-threaded sockets in the top of said body, an enlarged collar on each of said adjusting screws adjacent its upper end and having a portion thereof projecting into said recesses, respectively, for frictional engagement with the upper and lower walls of said recesses to adjust said side members to vary the position of said roller.
- 10 4. An apparatus of the character described having, in combination, a body, a chamber within said body for a coating liquid, a discharge opening for said liquid in the base of said chamber and presenting an elongated concave recess across a portion of its under surface, a roller of like curvature to said recess, a plurality of closely positioned parallel grooves about the circumference of said roller to transfer liquid from said chamber to a surface to be coated, a pair of plates on opposite sides of said body for pivotally supporting said roller with a portion thereof engaged within said recess, and means for positively moving said plates to change the position of said roller with reference to said discharge opening.
- 15 5. An apparatus of the character described having, in combination, a body, a chamber within said body for a coating liquid, a discharge opening for said liquid in the base of said chamber and presenting an elongated concave recess across a portion of its under surface, a roller of like curvature to said recess having a cylindrical outer surface and a plurality of closely positioned parallel grooves formed about said cylindrical surface from one end to the other thereof, a pair of plates on opposite sides of said body and non-rotatable with reference thereto for pivotally supporting said roller with a portion thereof engaged within said recess and holding said roller in axial parallelism with said recess, and means for positively moving said plates to change the position of said roller with reference to said discharge opening.
- 20 6. An apparatus of the character described having, in combination, a body, a chamber within said body for a coating liquid, a discharge opening for said liquid in the base of said chamber and presenting an elongated concave recess across a portion of its under surface, a roller of like curvature to said recess having a cylindrical outer surface and a plurality of closely positioned parallel grooves formed about said cylindrical surface from one end to the other thereof, said grooves being of shallow depth and of a width of from .001 to .0012 of an inch, a pair of plates on opposite sides of said body and non-rotatable with reference thereto for pivotally supporting said roller with a portion thereof engaged within said recess and holding said roller in axial parallelism with said recess, and means for positively moving said plates to change the position of said roller with reference to said discharge opening.

ROBERT A. MOORE. 140
